UNITED STATES PATENT OFFICE.

THOMAS E. NININGER, OF AMSTERDAM, VIRGINIA.

COOKING STOVE OR RANGE.

SPECIFICATION forming part of Letters Patent No. 779,130, dated January 3, 1905.

Application filed July 1, 1902. Renewed June 8, 1904. Serial No. 211,657.

To all whom it may concern:

Be it known that I, THOMAS E. NININGER, of Amsterdam, in the county of Botetourt, State of Virginia, have invented certain new and useful Improvements in Cooking Stoves or Ranges; and I do hereby declare the following to be a full, clear, and exact description of the same, reference being had to the accompanying drawings, forming a part of this specification, and to the letters of reference marked thereon.

This invention relates to improvements in cooking stoves or ranges wherein the cooking of the articles of food may be done either by steam heat or by the heat from the fire, or both; and it has for its object to provide such a stove which shall be simple in construction and easily operated.

To this end the invention consists in certain novel details of construction and combinations and arrangements of parts, all as will be now described, and the particular features of novelty pointed out in the claims.

Referring to the drawings, Figure 1 is a vertical sectional view of a stove constructed in accordance with this invention looking from the rear. Fig. 2 is an end elevation. Fig. 3 is a top plan view. Fig. 4 is a detail perspective view of the removable fire box or drawer.

Similar letters of reference in the several figures indicate the same parts.

In the practical embodiment of my invention there is provided at substantially the center of the body of the stove a chamber or compartment A, within which is located the fire-box. This compartment extends from front to rear of the stove-body, and the fire-box, preferably in the form of a rectangular box or drawer B, as shown in Fig. 4, is slid in this chamber, resting on the bottom thereof. The fire-box B is in length the same as the depth of the chamber A, but is preferably but half as high, a door b being employed to close the compartment A when the fire-box is in place, as will be understood from an inspection of Fig. 1. To one side of the central fire-chamber is located a water-tank C, a water-space c being left between the rear wall c' of the water-tank and central chamber A. Communication between the water-tank C and water-

space c is preferably established by having the rear wall of the water-tank stop a short distance from the bottom of the tank, as shown in Fig. 1.

Located above the water-tank C is an oven 55 D, having double walls, a steam-space d being thus formed about the oven, so that steam may pass around the outside of the inner wall and furnish sufficient heat for cooking.

As will be seen from Fig. 1, the water-space c leads directly into the steam-space d, surrounding the oven D, said steam-space d being practically a continuation of the water-space c.

For drawing off the water of condensation 65 from the steam-space d and also to allow for a continuous circulation of steam through the steam-space I provide a cock E', controlling communication between the steam-space and water-tank and operated by a suitable handle 70 e, extending out in convenient position to be manipulated.

As it is sometimes desirable or necessary to cook articles by the direct action of the steam, I have provided in the lower wall or base d' 75 of the oven D an opening whereby steam may enter the oven D from the steam-space d, said opening being closed when desired by a valve d². I also provide a cock d³ in the bottom of the oven D and leading into the water-tank, 80 through which water of condensation and steam may be drawn off from the interior of the oven D, said cock being controlled by a suitable handle d⁴. A cock h is provided for drawing hot water when desired. 85

At the opposite side of the stove from the steam-oven I locate an oven E, having double walls, a space e being formed around which the heat and products of combustion from the fire circulate, passing out through the smoke-pipe e'. When it is not desired to use this oven, the heat may be caused to pass directly out through the pipe e' by means of the damper F, as will be readily understood from Fig. 1. Articles may also be cooked upon the top 95 of the oven E and central chamber A, lids f being provided to close openings therein.

From the above description it will be seen that the water-space c being located immediately next to the fire-box the water will be 100

readily heated and steam quickly produced, thus facilitating the cooking of the articles. By locating the fire-chamber centrally of the stove no heat is lost in reaching the oven or 5 the water, as is the case where the heat is carried through long flues or passages.

The stove is compact and simple in construction and is adapted to the burning of wood, making it especially desirable for use 10 in isolated sections where other fuel is not obtainable.

Having thus described my invention, what I claim as new, and desire to secure by Letters Patent, is—

15 1. In a cooking-stove the combination with the centrally-located fire-chamber, the water-tank located within the stove, the water-space between the tank and central fire-chamber, the oven located above the water-tank, the 20 steam-space surrounding said oven and connecting with the water-space; substantially as described.

2. In a cooking-stove the combination with the centrally-located fire-chamber, the water- 25 tank, the water-space between the fire-box and tank, the oven located above the water-tank and next the fire-box, the steam-space surrounding said oven, and communicating with

the water-space and a cock leading from the steam-space into the water-tank; substantially 30 as described.

3. In a cooking-stove, the combination with the centrally-located fire-chamber, the water-tank located within the stove-body, the water-space located next the fire-box and communicating with the water-tank, the oven located above the water-tank, the steam-space surrounding the oven and communicating with the water-space, the cocks leading from the water-tank and the steam-space and oven and 40 a valve for introducing steam to the interior of the oven; substantially as described.

4. In a cooking-stove, the combination with the centrally-located fire-chamber, the water-tank, the oven located above the water-tank, 45 the steam-space surrounding said oven, a second oven, a heat space or flue surrounding said oven, and communicating with the fire-chamber, a smoke-pipe and a damper for causing the products of combustion to pass around 50 the second oven or through the smoke-pipe; substantially as described.

THOMAS E. NININGER.
